UNITED STATES PATENT OFFICE

2,068,550

REFRIGERATOR CABINET

James L. Knight, Erie, Pa., assignor to General
Electric Company, a corporation of New York

Application June 19, 1935, Serial No. 27,363

7 Claims. (Cl. 62—89)

My invention relates to refrigerator cabinets, and more particularly to an improved compartment for use within a refrigerator cabinet for the purpose of maintaining food, such as butter and the like, at a temperature suitable for the preservation thereof, but higher than that within the main refrigerated compartment of the cabinet.

In order that food stuffs may properly be preserved, it is necessary to maintain the cabinets of domestic refrigerators at a temperature so low that butter kept therein is too hard for spreading. For this reason butter, for example, kept in a refrigerator cabinet must be allowed to warm before it is in condition for serving at the table. A thermally insulated auxiliary compartment may be provided within a refrigerator and may be arranged so that sufficient heat will be conducted into the compartment to maintain it at a temperature higher than that within the main compartment. Since the leakage of heat into a refrigerated cabinet varies greatly due to the variation of temperature with the seasons of the year, it is desirable to provide some arrangement for adjusting the temperature within the auxiliary compartment. Accordingly, it is an object of my invention to provide within a refrigerator cabinet a thermally insulated auxiliary compartment warmed by conduction of heat into the same and provided with a device for varying the amount of heat conducted thereto in order to maintain the auxiliary compartment at a temperature higher than that within the refrigerated compartment and suitable for the storage of butter or the like so that it will be in suitable condition for immediate use at the table.

Further objects and advantages of my invention will become apparent as the following description proceeds, and the features of novelty which characterize my invention will be pointed out with particularity in the claims annexed to and forming a part of this specification.

For a better understanding of my invention, reference may be had to the accompanying drawing, in which Fig. 1 is a perspective view of a household refrigerator provided with an auxiliary compartment embodying my invention and mounted in the door thereof, and Fig. 2 is an enlarged sectional view of the auxiliary compartment arranged in the door of the refrigerator shown in Fig. 1.

Referring now to the drawing, in Fig. 1 I have shown a household refrigerator comprising a cabinet 10 having a door 11 and provided with a refrigerating machine including a motor and

compressor casing 12, a condenser 13, and an evaporator 14 for cooling the refrigerated compartment 10a within the cabinet 10. The cabinet 10 is constructed of inner and outer metal walls having thermal insulation therebetween and connected about the door opening by strips 15 of heat insulating material. The door 11 is of similar construction to that of the cabinet and comprises inner and outer metal walls 16 and 17 connected by strips 18 of heat insulating material.

During the operation of the refrigerating machine, the evaporator 14 is maintained at a temperature sufficiently low for freezing the contents of trays 19 arranged within the evaporator and 15 for maintaining the air within the compartment 10a at a temperature sufficiently low for preserving food therein. Butter or the like placed within the compartment 10a will be maintained at a temperature so low that it is difficult to spread 20 when it is removed from the refrigerator.

In accordance with my invention, I preserve butter or similar articles of food at a temperature high enough to permit spreading thereof when it is removed from the cabinet, by providing a thermally insulated auxiliary compartment 25 within the cabinet door 11 provided with a door 20 hinged at 21 to the inner wall 16 of the cabinet door, a catch 22 being provided to hold the door 20 closed. A knob 23 is provided in 30 order to adjust the temperature within the auxiliary compartment in a manner hereinafter described.

The construction of the auxiliary compartment can clearly be seen in Fig. 2, where I have shown the inner and outer walls 16 and 17 of the door 11 connected by strips 18 and provided with thermal insulation 24 therebetween. The auxiliary compartment at 25 is formed by a metal liner 26 inserted within the insulation 24 and secured to the wall 16. The metal liner 26 is secured to the wall 16 and insulated therefrom by a gasket 27 of rubber or other suitable material. The door 20 fits against the gasket 27 and thereby 40 closes the auxiliary compartment 25. Since the liner 26 is inserted within the insulation 24, a portion 24a of the insulation between the liner and the outer wall 17 is of substantially reduced thickness. During hot weather, as in the summer time, there will be sufficient leakage of heat through the portion 24a of the insulation to maintain the temperature within the compartment 25 sufficiently high that butter or the like may be preserved therein without undue 50 55

hardening. During the winter, however, when the temperature of the room may be kept as low as 70° F., it is desirable to increase the leakage of heat from the outside of the cabinet to the compartment 25. For this reason, I provide a heat conducting member 28 of suitable sheet metal, which is shown in Fig. 2, secured to the outer wall 17 and arranged in contact with the liner 26 of the compartment 25. The member 28 provides a heat conducting path between the wall 17 and the liner 26 and greatly increases the flow of heat from the outside air to the compartment 25. The member 28 is provided with slots 29 and is slidably mounted on wall 17 by rivets 30 engaging the slots 29 and holding the member 28 in good heat exchange relation with the wall 17. In order to shift the position of the member 28, so that direct contact between the wall 17 and the liner 26 may be broken during hot weather, I provide a compression spring 31 mounted between a lug 32 secured to the wall 17 and a seat 33 on the member 28. This spring continually presses the member 28 downwardly against the end of a bell crank 34 operated by the knob 23, and tends to push the member 28 away from the liner 26. The bell crank 34 is pivoted at 35 to a lug 36 secured to the liner 26 and is secured to a shaft 37 of the knob 23 by a slot 38 and pin 39 connecting the bell crank to a block 40 threaded on the shaft 37. By turning the knob 23, the position of the bell crank is changed so that the end 41 thereof moves up or down as desired. When the crank 34 is downwardly turned in a clockwise direction from the position shown in Fig. 2, the spring 31 will force the heat conducting member 28 out of contact with the liner 26, thereby breaking the heat conducting connection between the wall 17 and liner 26.

When it is desired to utilize the auxiliary compartment 25, a vessel 42 containing a package 43 of butter or other similar food is placed within the compartment and the knob 23 is turned to the desired position. In the summer, when the temperature of the air surrounding the cabinet is high, the knob 23 is turned to a position such that the member 28 is not in contact with the liner 26, and there is a minimum leakage of heat into the auxiliary compartment 25. During the winter the knob 23 is turned to force the member 28 against the spring 41 so that a heat connecting path is established between the liner 26 and the outer wall 17, and there is a greater leakage of heat from the outer wall to the auxiliary compartment 25. During the operation of the refrigerator cabinet the compartment 25 will be maintained at a temperature intermediate that of the main refrigerated compartment of the refrigerator cabinet and that of the air surrounding the cabinet and sufficient heat will be abstracted from the compartment 25 to properly preserve the butter, but there will be sufficient leakage of heat into the compartment, so that the butter will be preserved at a temperature substantially higher than that of the refrigerated compartment and the consistency of the butter will be satisfactory for spreading.

While I have shown and described my invention in connection with a household refrigerator, other applications will readily be apparent to those skilled in the art. I do not, therefore, desire my invention to be limited to the particular construction illustrated, and I intend in the appended claims to cover all modifications within the spirit and scope of my invention.

What I claim as new and desire to secure by Letters Patent of the United States is:

1. A refrigerator cabinet including a refrigerated compartment, a thermally insulated compartment within said refrigerated compartment, means providing a path for the conduction of heat between the exterior of said cabinet and said thermally insulated compartment for maintaining the temperature within said thermally insulated compartment above the temperature of said refrigerated compartment and within a temperature range suitable for preserving butter and the like, and means co-operating with said first mentioned means and changing the thermal conductivity of said path for varying the amount of heat transmitted to said thermally insulated compartment.

2. A refrigerator cabinet including a refrigerated compartment, a thermally insulated compartment within said refrigerated compartment, a metal liner for said thermally insulated compartment, and means including a metal heat conducting member engaging said metal liner and in heat exchange relation with the air surrounding said cabinet for conducting heat from the air surrounding said cabinet to said thermally insulated compartment and for maintaining the temperature in said thermally insulated compartment above the temperature within said refrigerated compartment and within a temperature range suitable for preserving butter and the like.

3. A refrigerator cabinet including a refrigerated compartment, a thermally insulated compartment within said refrigerated compartment, a metal liner for said thermally insulated compartment, means including a metal heat conducting member engaging said metal liner and in heat exchange relation with the air surrounding said cabinet for conducting heat to said thermally insulated compartment and for maintaining the temperature in said thermally insulated compartment above the temperature within said refrigerated compartment and within a temperature range suitable for preserving butter and the like, and means breaking the engagement between said heat conducting member and said inner liner for reducing the amount of heat conducted to said thermally insulated compartment.

4. A refrigerator cabinet having a refrigerated compartment, a thermally insulated compartment arranged within said refrigerated compartment, a metal liner for said thermally insulated compartment, means providing conduction of heat through the outer wall of said cabinet to said metal liner for maintaining the temperature within said thermally insulated compartment higher than that within said refrigerated compartment, and means varying the conduction of heat to said metal liner for varying the temperature within said thermally insulated compartment.

5. A refrigerator cabinet having inner and outer walls forming a refrigerated compartment, a thermally insulated compartment arranged within said refrigerated compartment, a metal liner for said thermally insulated compartment, means providing conduction of heat from said outer wall of said cabinet to said metal liner for maintaining the temperature within said thermally insulated compartment higher than that within said refrigerated compartment, and means including a heat conducting member movable into engagement with said outer wall and said metal liner for varying the conduction of heat to said

metal liner and for varying the temperature within said thermally insulated compartment.

6. A refrigerator cabinet having inner and outer walls forming a refrigerated compartment, a thermally insulated compartment arranged within said refrigerated compartment, a metal liner for said thermally insulated compartment, means including a heat conducting member slidably mounted on said outer wall and connecting said inner liner and said outer wall for conducting heat from said outer wall to said thermally insulated compartment and for maintaining said thermally insulated compartment at a temperature higher than that within said refrigerated compartment, and manually operable means arranged to move said heat conducting member for breaking the heat conducting connection between said outer wall of said cabinet and said inner

liner to decrease the temperature within said thermally insulated compartment.

7. A refrigerator cabinet having inner and outer walls forming a refrigerated compartment, a thermally insulated compartment arranged within said refrigerated compartment, a metal liner for said thermally insulated compartment, means including a heat conducting member for providing a heat conducting path between said metal liner and said outer wall, means moving said heat conducting member for breaking the connection between said inner liner and said outer wall of said cabinet to decrease the temperature within said thermally insulated compartment, and means moving said heat conducting member for establishing the connection between said inner liner and said outer wall to increase the temperature within said thermally insulated compartment. 15
